UNITED STATES PATENT OFFICE.

ROBERT A. PITMAN, OF PHILADELPHIA, PENNSYLVANIA, ASSIGNOR TO TACONY IRON COMPANY, OF PHILADELPHIA, PENNSYLVANIA, A CORPORATION OF PENNSYLVANIA.

PERMANENT TWO-PART METAL MOLD.

No. 928,151.

Specification of Letters Patent.

Patented July 13, 1909.

Application filed December 30, 1908. Serial No. 470,008.

To all whom it may concern:

Be it known that I, ROBERT A. PITMAN, a citizen of the United States, residing at the city of Philadelphia, in the county of Philadelphia and State of Pennsylvania, have invented certain new and useful Improvements in Permanent Two-Part Metal Molds, of which the following is a specification.

My invention has relation to means for 10 poising and manipulating quickly the opening and closing of a permanent sectional metal mold for making different kinds or types of castings such as tubings, fittings etc., a familiar example of such castings being found in United States Letters Patent 15 No. 870,817, dated November 12th, 1907, granted to Edgar A. Custer, as well as in subsequent patents and applications for patents of the said Custer for making such 20 general character of castings.

The principal object of my present invention for employment in connection with the Custer system of making homogeneous and other character of metal castings depending 25 upon internal formations of the two-part molds, is to provide means for poising suspended hinged sections of the mold in order to be easily manipulated for quickly opening and closing the mold. This ease of manipulation of the mold being accomplished 30 by so poising the parts or sections of the mold at such points and in a manner as that in opening, the parts or sections are uniformly balanced, one section against the 35 other.

My invention stated in general terms, consists of a suspended permanent sectional metal mold provided with poising means and shifting devices arranged by the shifting, of quick opening and closing of the two-parts or sections of the mold, to respectively, 40 permit first of the pouring of molten metal into the interior thereof and second of the freeing of the cast or set structure, therefrom.

The nature, scope and characteristic general features of my present invention will be more fully understood from the following 45 description taken in connection with the accompanying drawings forming part hereof, in which—

Figure 1, is a side elevational view of a suspended metal sectional mold embodying characteristic main features of my invention, 50 this view showing the parts or sections of

the mold in respectively two different positions, closed and open, with respective positions of the shifting devices and poising means in their relations to each other, in said defined positions of the sectional mold; 60 and Fig. 2, is a top or plan view of the suspended sectional permanent metal mold, in a closed position.

Referring to the drawings a , a^1 , are two vertical standards with extensions a^2 , a^2 , as 65 clearly shown in Fig. 1. The standard a , at the top is provided with a movable latching device a^3 , for being brought into and out of engagement with a lever-arm b^3 , of a hinged sectional metal mold B. This mold B, as 70 shown, is composed of two complementary parts or sections b , b^1 , of rectangular shape, hinged at b^2 , b^2 , to each other. The interiors of the two-parts or sections of the mold are provided with recesses to form together a 75 suitable cavity b^4 , and having channelways leading thereto, not shown, from the pour-holes b^5 , b^5 , as shown in Fig. 2, arranged at suitable distances apart about the meeting ends of one part or section of the mold with 80 the other part thereof.

In each of the extensions a^2 , a^2 , of the standards a , a^1 , are provided preferably detachable roller-bearings c , c , for engaging journals b^6 , b^6 , of the part or section b , of 85 the mold B, for easily or sensitively poising the said sectional metal mold in a suspended condition from the standards, as fully shown in Fig. 2. From the part b^1 , of the mold on both sides project journals carrying rollers b^8 , b^8 , for by shifting one part or section of the mold with respect to the other, as fully shown in Fig. 1, the said rollers riding along the rear vertical edges or bearings of the vertical standards a , a^1 , assume 90 respectively, different positions on the standards edges or bearings according to the position of the one part of the mold with respect to the other thereof. The functional object of permitting the riding of the 95 rollers b^8 , along the standards, in the opening and closing of the sections of the mold, is to prevent the section b^1 , of the mold B, falling forward onto the section b , but other arrangements for accomplishing the same result may be substituted for that specifically 100 described and shown. When the sectional mold B, is in a closed position, as shown in Fig. 1, the lever-arm b^3 , will occupy a locked position in engagement with the latching 105

110

device a^3 . On the other hand when in an open position the lever-arm b^3 , will assume the broken line longitudinal position in Fig. 1, with the part b^1 , of the mold elevated into 5 an angular relation with respect to the part b , as shown in broken outline in Fig. 1, for removing the structure set while the two parts of the mold B , was in a closed condition, by simply opening the same in the 10 manner hereinbefore explained. In the practice of the said Custer castings system referred to, it is desirable to be able to so manipulate the sectional metal mold as that almost the instant pouring of the molten 15 metal into the mold has been accomplished the mold can be easily opened to free the structure set in the mold therefrom and to do this with facility, that is, without undue labor is the object of my invention by so 20 poising the suspended sectional mold so that simply manipulating the lever-arm b^3 , of one part of the mold will either quickly close or open the same. In the one instance to permit of the pouring of the molten metal 25 into the mold and in the other to liberate the structure cast from the mold in order that the homogeneity established may be insured and the qualities of the structure for subsequent machining or threading be 30 had.

Having thus described the nature and objects of my invention, what I claim as new and desire to secure by Letters Patent is:—

1. The combination with standards having bearing-means, of a sectional metal mold having journals arranged to engage said bearing-means to support the mold in a sensitive suspended condition and provided with traveler bearings for riding the 35 standards and with means to open and close the sectional mold, substantially as and for the purposes described.

2. The combination with standards having roller bearing-means, of a sectional permanent metal mold provided with journals arranged to engage said means so as to support said mold in a sensitive suspended condition, means connected with one section of the mold to open and close the sections of said mold and means connected with the 45 mold to prevent when the sections are parted from one another, the same falling onto one another, substantially as and for the purposes described.

3. The combination with standards having extensions provided with bearing-means, a sectional metal mold having journals arranged to engage said means to support the mold in a sensitive suspended condition and provided with traveler bearings for riding the standards, a device for opening and closing the sectional mold and means for locking and unlocking said device, substantially as and for the purposes described.

4. The combination with standards having bearing-means, a permanent sectional mold having traveler means, journals and a lever-arm, said journals engaging said bearing-means, said traveler means adapted to ride said standards and said lever-arm adapted to open and close said sectional mold and a device connected with one of said standards and arranged for latching said lever-arm, substantially as and for the purposes described.

In witness whereof, I have hereunto set my signature, in the presence of two subscribing witnesses.

ROBERT A. PITMAN.
